UNITED STATES PATENT OFFICE.

MOSES B. DISKIN, OF NEW YORK, N. Y.

SHEET-APPLYING MACHINE.

1,355,390.

Specification of Letters Patent. Patented Oct. 12, 1920.

Application filed February 20, 1919. Serial No. 278,158.

To all whom it may concern:

Be it known that I, MOSES B. DISKIN, a citizen of the United States, residing at New York, in the county of New York and State of New York, have invented certain new and useful Improvements in Sheet-Applying Machines; and I do hereby declare the following to be a full, clear, and exact description of the invention, such as 10 will enable others skilled in the art to which it appertains to make and use the same.

The present invention relates to a machine for applying sheets or flaps to boxes, and the machine is particularly intended for 15 use in pasting tissue paper or other sheets to cardboard or paper boxes, so as to provide flaps to extend over the mouths of the boxes for protecting the contents thereof, although the machine can be used for other 20 purposes, that is, for pasting sheets to other objects.

One of the objects of the invention is to provide such a machine having novel means for receiving and holding a stack of sheets 25 for receiving paste and then receiving the box or object to which the uppermost sheet is attached.

Another object is to provide novel means for applying paste to the sheets.

30 A further object is to provide means for clamping down the sheets during the application of paste thereto, to prevent the displacement of the sheets.

A still further object is the provision of 35 novel means for pressing the box or other object against the sheet to which the paste is applied, so as to attach or paste them together firmly.

The invention also has for its object the 40 provision of such a machine comprising a novel assemblage and combination of the component elements in order that the machine will be practical and efficient in operation, and so that the machine can be 45 adjusted for sheets and boxes of different sizes.

With the foregoing and other objects in view which will be apparent as the description proceeds, the invention resides in the 50 construction and arrangement of parts hereinafter described and claimed, it being understood that changes can be made within the scope of what is claimed without departing from the spirit of the invention.

The invention is illustrated in the accompanying drawings, wherein:—

Figure 1 is a side elevation of the machine showing the parts in position as when the paste is applied to the uppermost sheet.

Fig. 2 is a front view thereof.

Fig. 3 is an enlarged plan view of the sheet receiving and holding means, showing the paste applying means in section.

Fig. 4 is a fragmentary elevation of the presser device for pressing the box and 65 sheets together.

Fig. 5 is a cross sectional detail taken on the line 5—5 of Fig. 4.

In carrying out the invention, there is provided a suitable frame 1, in which is 70 mounted a driving shaft 2, and a pulley wheel 3 driven in any suitable manner is rotatable on one end of the shaft 2 and is connected thereto by means of a clutch 4 to operate the machine as desired by the operator. The clutch 4 is connected by any suitable mechanism 5 with a treadle 6, in order that the operator can start and stop the machine at will. The frame 1 carries a suitable table 7 on which the work is done. 75

The magazine for the sheets is located above the forward edge portion of the table 7, which is provided with a downwardly extending ledge 8 having a depending flange 9. Angular blocks 10, 11 and 12 are seated 85 on the ledge 8 and against the flange 9. Said blocks are provided with stems 13 to extend rearwardly through a longitudinal slot 14 in the flange 9 and on which nuts 13' can be threaded for clamping said locks in 90 adjusted position. The blocks 12 are used as spacers or fillers between the end blocks 11 and the intermediate block 10, and any number of blocks 12 can be used according 95

to the position of the blocks 11 and the distances thereof from the block 10 according to the length of the sheets and boxes for which the machine is adjusted. By loosening the blocks 11, they can be slid longitudinally according to the length of the sheet and box, and the blocks 12 can be removed and applied as needed. The stack of sheets 15 is seated on the table 7 over the forward edge thereof and on the blocks 10, 11 and 12. The magazine includes retaining fingers 16 pivoted to the blocks 11 and extending upwardly at an angle to one another, and raised yieldingly by springs 17 100

so that the forward edges of the sheets 15 rest against the fingers 16 which form the front wall of the magazine. The magazine further includes end members 18 seated on the table 7 and adjusted longitudinally of the table, the feet of said members 18 having bolts 19 or the like working in a longitudinal slot 20 in the table 7 to permit of adjustment according to the lengths of the sheets. The end members 18 can thus be readily adjusted for sheets of different sizes, as well as the blocks 11 carrying the fingers 16.

The end members 18 carry means for clamping the sheets down or holding the stack down during the application of paste, so that the uppermost sheet to which the paste is applied will not be displaced or taken off of the stack by the return movement of the paste applying means. Thus, vertical rods 21 are slideable in the members 18, and presser feet or plates 22 are connected to the lower ends of the rods 21, and work in slots 23 in the members 18. The feet 22 are preferably of L-shape, as seen in Fig. 3, so as to extend forwardly and bear down on the sheets near their forward edges adjacent to which the paste is applied. Expansion coiled springs 24 surround the rods 21 and are confined between the upper ends of the members 18 and heads or members 25 on the rods 21, so as to raise said rods when they are free to do so, and thus raise the feet 22 off of the sheets. In this way, the feet 22 are normally raised out of the way off of the stack of sheets.

The paste applying means includes two pairs of parallelogram arms 31 at opposite ends of the machine pivoted at vertically spaced points to standard 1' secured on the table 7, and said arms are swingable upwardly and downwardly, and vertical parallelogram links 29' are pivoted to the free ends of the arms 31 at the opposite ends of the machine and remain in vertical position as the arms are swung upwardly and downwardly, and maintain a parallelogram movement from the paste applying means. A vertically movable slide 30 is carried by each link 29' and has an upwardly projecting rod or stem 28 passing slidably through a cross bar 33 which connects the links 29'. Coiled expansion springs 28' are disposed on the rods 28 between the bar 33 and slides 30 to move said slides yielding downward, and nuts 30' are disposed on the upper terminals of the rods 28 to limit their downward movement. A longitudinal rod 29 has its terminals secured to the slides 30 to move upwardly and downwardly therewith, and a longitudinal row of paste applying blocks 35 are mounted on the rod 29, each block being engaged on the rod near one end, so that the block can be swung upwardly and downwardly. The intermediate block 35' is

wider than the others, and nuts 32 are threaded on the rod 29 at the opposite ends of the blocks 35 for clamping them together. When the nuts 32 are loosened, those blocks 35 beyond the ends of the sheets 15 can be swung upwardly out of the way, as seen in Fig. 2, and the nuts 32 are then tightened to clamp the blocks in position. It will be noted that only the blocks 35 which are turned down will come into contact with the paste and sheets. Thus, by swinging the blocks 35 into and out of operative position, the paste applying means can be adjusted to the length of the sheet or strip of paste which is to be applied.

A paste pot or pan 60 is supported by and between the standards 1' and has supported for rotation therein a roller 61 which is so arranged that when the arms 31 are swung upwardly, those paste applying blocks 35 which are set downwardly to active position with respect to the rod 29, will pass over and contact with the top part of the roller 61, thus not only rotating the roller 61 but also applying paste to the lower ends of the active blocks 35. Thus, as the paste applying means is moved upwardly and downwardly, this rotates the roller 61 so that it will elevate the paste, and the paste is thus applied to the active blocks 35, those that are turned up not coming into contact with the roller.

The movement of the paste applying means is used to operate the feet 22, and for this purpose, blocks 34 are mounted slidably on the bar 33 and are held in adjusted positions by means of set screws 34' carried thereby. These blocks 34 have brackets 36 extending rearwardly and in which vertical rods 21' are slideable. These rods 21' have collars 25' at their lower ends to seat on the collars 25, and coiled expansion springs 26 surround the rods 21' and are confined between the bracket 36 and collars 25' to move the rods 21' downwardly with respect to the brackets, such downward movement being limited by nuts 27' on the upper terminals of said rods. Thus, when the arms 31 are swung downwardly, the rods 21' will move downwardly with the brackets 36, and the rods 21' will seat on the upper ends or collars 25 and the rods 21. The further downward movement of the brackets 36 will compress the springs 26, thus forcing the rods 21 downwardly against the tension of the springs 24, and thus moving the feet 22 downwardly until they come to rest on the stack of sheets thus holding the uppermost sheet down firmly in place and preventing it from being dislodged during the application of the paste. The uppermost sheet is thus held down in place during the application of paste thereto near its forward edge, and will also be held down during the initial upward movement of the paste applying means until same is withdrawn from the

sheet when the upward movement of the rods 21' will release the rods 21 and permit the springs 24 to again raise the feet 22. This will prevent the uppermost sheet from being 5 lifted off of the stack by its tendency to adhere to the blocks 35. The blocks 34 can be adjusted according to the members 18.

The paste applying means is operated from the shaft 2. Thus, one of the arms 31 10 has a lever 37 connected by a link 38 with a lever 39 fulcrumed to the frame 1 and carrying a roller 40 bearing against a cam 41 secured on the shaft 2. The cam 41 swings the lever 39 in one direction to move the 15 paste applying means downwardly to apply the paste, and a spring 42 raises the arms 31 as the cam 41 completes its rotation.

The box or object 43, after the paste is applied to the uppermost sheet 15, is then 20 introduced over said sheet, as seen by dotted lines in Fig. 1. The top of the box can pass over the forward portion of the stack of sheets and over the blocks 11, 12 and 10, to bring the edge of the top wall of the box 25 over the forward edge of the uppermost sheet. This introduction of the box or object is done by hand when the paste applying means has been raised.

The presser device for applying pressure 30 to the box or object embodies a longitudinal rock shaft 53 journaled underneath the table 7 behind the ledge 8, and arms 44 pivoted, as at 45, to the ends of the table 7. Each arm 44 carries a transversely movable slide 35 46 having a rod or stem 47 slidable through an ear 44' of the arm 44, and coiled expansion springs 48 surround the arms 47 and are confined between the slides 46 and ears 44' to move the slides 46 downwardly.

40 Nuts 49 upon the upper terminals of the rods 47 limit downward movement. A longitudinal presser bar 50 has its terminals secured to the slides 46, and is movable downwardly with the arms 44 to bear on the box 45 or object above the paste and press said box down firmly, thus pasting the box and uppermost sheet together at the inside of the box adjacent to the edge thereof. In order to prevent the bar 50 from turning in the 50 slides 46, pins 51 extend upwardly from the bar 50 through ears 52 extending from the slides 46. The arms 44 are normally swung upwardly and rearwardly to move the bar 50 out of the way of the paste applying 55 means, as seen in Fig. 1, and when the arms 44 are swung forwardly and downwardly, the bar 50 will seat on the box or object which has been introduced over the sheets, and it will be noted that the downward 60 movement of the arms 44 will compress the springs 48 thus obtaining the desired pressure and also a yielding movement of the presser bar or member 50.

The arms 44 and shaft 53 have gear seg- 65 ments 54 meshing with one another, so that

said arms will be rocked by the shaft 53, which is provided with an arm 55 connected by a link 56 with a lever 57 fulcrumed to the frame 1 and having a roller 58 opposite to the roller 40 bearing against the cam 41. 70 The paste applying means and presser device are thus operated alternately, so that after the paste is applied and the paste applying means moved back or returned, the presser device is then brought into opera- 75 tion for pasting the box and sheet together. The presser device is returned by a spring 59.

In operation, the mechanism is started and stopped at will by controlling the clutch 80 4 through the medium of the treadle 6, or the like.

The paste applying means and presser device operate alternately, that is, when one is moving to active position, the other is 85 moving back or returning from active position. The paste applying means which is normally in vertical position with the active blocks 35 seating on the roller 61, first moves forwardly and downwardly so that 90 said blocks apply a strip of paste on the uppermost sheet of the magazine adjacent to the forward edge thereof, and said paste applying means then returns, and during the interval, the operator introduces the box 95 or object over the fingers 16. The presser device is then brought into operation, the arms 44 swinging forwardly and causing the presser bar 50 to press the box or object down on the paste, so that the box and sheet 100 will adhere. It will be noted that the downward pressure on the box or object will swing the fingers 16 downwardly, so that they will not interfere. Then, when the arms 44 are raised, this permits the box or 105 object to be withdrawn with the sheet that has been pasted thereto, and the fingers 16 can rise up again under the influence of their springs 17. This operation is repeated, it merely being necessary for the operator 110 to introduce and remove the boxes or objects as the paste applying means and presser device are moved away from the sheets, respectively. The operation is the same when the machine is adjusted for 115 sheets and boxes of different lengths, as will be apparent from the foregoing.

Having thus described the invention, what is claimed as new is:—

1. A sheet applying machine embodying a 120 table for supporting a stack of sheets, blocks adjustably mounted at one edge of the table to assist in supporting the sheets, members adjustable on the table for holding the sheet in place, and yieldable means carried by 125 said blocks forming one wall of a magazine for the sheets, and movable downwardly.

2. A sheet applying machine embodying a table for supporting a stack of sheets, 130

- blocks adjustably carried by the table at one edge to assist in supporting the sheets, members adjustable on the table for holding the sheets therebetween, and fingers pivoted to some of said blocks and extending upwardly at an angle to retain the sheets in place and yieldable downwardly to permit a box or object to be pressed down on the sheets over said fingers.
10. 3. A sheet applying machine embodying a magazine for a stack of sheets, paste applying means to and from the sheets to apply paste to the uppermost sheet, normally raised means movable downwardly to press down on the stack, and means for yieldingly moving the last named means downwardly with the paste applying means when it contacts with the uppermost sheet.
4. A sheet applying machine embodying a magazine for a stack of sheets, paste applying means movable downwardly and upwardly to and from the sheets to apply paste to the uppermost sheet, spring-raised means movable downwardly to press down on the stack of sheets, and yieldable means movable with the paste applying means to contact with and depress said pressing means when the paste applying means moves into and out of contact with the uppermost sheet.
5. A sheet applying machine embodying a magazine for a stack of sheets including a member forming one wall of the magazine, a rod slidable vertically in said member and having a portion to bear on the stack of sheets, means for normally raising said rod, paste applying means movable to and from the sheets to apply paste to the uppermost sheet, and means for depressing said rod when the paste applying means moves into and out of contact with the uppermost sheet.
6. A sheet applying machine embodying a table for supporting a stack of sheets, relatively adjustable members on the table for holding the sheets therebetween, rods slidable vertically in said members and having

means at their lower ends to bear on said sheets, means for normally raising said rods, paste applying means movable downwardly and upwardly to apply paste to the uppermost sheet, relatively adjustable members carried by the paste applying means, and yieldably depressed members carried by the last named members to move said rods downwardly when the paste applying means moves into contact with the uppermost sheets.

7. A sheet applying machine embodying a table for supporting a stack of sheets, relatively adjustable magazine members on the table for holding the sheets therebetween, rods slidable vertically in said members and having means at their lower ends to bear on the stack of sheets, means for normally raising said rods, the parallelogram device, paste applying means carried by said device to move downwardly and upwardly into and out of contact with the uppermost sheet for applying paste thereto, relatively adjustable members carried by said device, and spring depressed rods carried by the last named members to seat on the aforesaid rods when the paste applying means moves into contact with the uppermost sheet.

8. A sheet applying machine embodying a magazine for holding a stack of sheets, means for applying paste on the uppermost sheet, and a presser device for pressing a box or object on the uppermost sheet over the paste, including rocker arms, spring-pressed slides carried thereby, and a presser bar extending over the magazine to bear down on the box or object and having its ends attached to said slides.

In testimony whereof I have signed my name to this specification in the presence of two subscribing witnesses.

MOSES B. DISKIN.
